UNITED STATES PATENT OFFICE.

JAN CRNOEV, OF ST. LOUIS, MISSOURI.

NECKTIE HOLDER.

Application filed September 25, 1922. Serial No. 590,391.

To all whom it may concern:

Be it known that I, JAN CRNOEV, a citizen of Serbia, residing at St. Louis, Missouri, have invented a certain new and useful Improvement in Necktie Holders, of which the following is a full, clear, and exact description, such as will enable others skilled in the art to which it appertains to make and use the same, reference being had to the accompanying drawings, forming part of this application.

My invention relates to necktie holders of the type shown in my prior Patent No. 1,400,663, and in my copending application Serial Number 569,115.

My present invention consists in improvements upon the above-mentioned structures, the objects of my invention being to better adapt the holder for various styles, heights, and adjustments of collars, and to provide positive securing means for the assembled portions of my collar holder which are preferably made adjustable one with the other to accommodate different heights of collars, etc.

An incidental object of the invention is to make such positive securing means easily releasable. I also desire to form the holder as economically as possible and in the present construction utilize materials which will permit of inexpensive construction.

In the accompanying drawings which illustrate my invention—

Figure 1 is a rear elevation of a preferred form of necktie holder.

Figure 2 is a side elevation of the same.

Figure 3 is a horizontal section taken on line 3—3 of Figure 2.

Figures 4 and 5 are elevations, corresponding to Figures 1 and 2, of a modified construction.

Figure 6 is a horizontal section taken on line 6—6 of Figure 5.

In the preferred form illustrated in Figures 1, 2, and 3, the holder comprises a body member adapted to support the necktie and a two-part adjustable collar button engaging member assembled with the body member. The body member is Y-shape and includes a stem 1 which mounts arms 2. Arms 2 are both formed from a single piece of wire,

the ends 3 of which are bent in individual planes to provide the arm with a substantial bearing area in the collar folds and so to determine the angle of the stem relative to the collar. Arms 2 are preferably rigidly united with stem 1 by being soldered thereto or otherwise fixed thereon. The stem 1 of the body member is shown as consisting of a flat strip doubled upon itself and receiving a narrower flat strip 4 between its folds. Strip 4 is bent upwardly and terminates in a rearwardly extending flange 5, the width of which is about half that of strip 4.

The other part of the collar button engaging member consists of a split strip 6, the legs of which are bent into U-shaped sections 7, the open ends of which oppose each other and one leg of each section is provided with a series of notches or teeth 8, each having a horizontal upwardly facing edge and an inclined downwardly facing edge. Notches 8 on the two legs oppose each other and are adapted to receive flange 7 of strip 4 between them. Notches 8 may be slid over flange 5 in one direction but will positively engage the flange to prevent sliding movement in the opposite direction. With the parts as shown in Figures 1 and 2, flange 5 is shown as just entering the lowest pair of notches on member 6. Obviously the collar holding portion of the device may be moved upwardly along member 6 with practically no resistance until the ends 3 of the Y arms engage the collar fold. The horizontal edges of the teeth will positively engage the bottom of flange 5 to prevent its moving downwardly. Thus the tie will be held snugly against the upper portion of the collar.

The top of member 6 is provided with an opening 9 which will receive the head of a collar button and the axis of which is disposed substantially at right angles to the plane of member 6. Extending upwardly from the upper edge of opening 9 is a smaller recess 10 adapted to engage the shank of a collar button and this portion of member 6 is bent as indicated in Figure 2 and when the device is in use this bent portion will engage the front of the neck band

and will cooperate with the ends 3 of the Y arms to maintain the angle of the collar holder in the collar.

The lower portions of U-shaped sections 7 of member 6 are provided with individual fingers 11 and 12, respectively, finger 11 being attached to the right-hand section 7 and extending outwardly from the lefthand side of member 6, finger 7 being attached to the lefthand section 7 and extending outwardly from the righthand side of member 6, and parallel with the outwardly extending portion of finger 11. By means of this disposition of fingers 11 and 12 they may be easily gripped between the thumb and finger of the hand and upon being pressed together will separate sections 7 to which they are attached so as to release flange 5 from notches 8 and permit lowering of the Y-stem.

In the modification shown in Figures 4, 5 and 6, the collar engaging member 13 is hinged to the collar button engaging member 14 and the sliding portion of the collar button engaging member consists of a wire 15 doubled upon itself to form the loop 16. The hinged portion 14 has its sides folded over as best shown in Figure 6 and one of these sides is provided with notches 20, both the upper and lower faces of each notch being horizontal. One leg of the sliding wire 15 extends downwardly in the groove formed by the unnotched side of member 14 and at its lower end is provided with a return bend 17 extending clear across the inner surface of member 14. The other downwardly extending leg of member 15 terminates short of return bend 17 in a portion 18 which is bent horizontally to extend through the space between the bent-over portion of member 14 and then curves around the notched portion at 19 to engage the back of member 14. There is sufficient elasticity in member 15 to thrust horizontal shoulder 18 into notches 20 in member 14. The loop 19 affords a finger engaging element by which the notch engaging leg of member 15 may be pressed toward the other leg to release shoulder 18 from the notches in member 14 and permit the two members to be slid relatively to each other.

In this modification the arms of the collar holding member are formed of the same flat material as the stem and are shaped throughout their length to slip in between the folds of the collar to maintain the desired angle of the holder and the collar or shirt. Loop 16 of wire member 15 is bent at its upper end similarly to the upper portion of member 6 in the preferred form so as to cooperate with the arms 21 of the Y-member in positioning the necktie holder.

By means of the constructions described, one of the main objections to devices of this type are overcome. Such devices as have been placed on the market while adapted to

afford a snug fit to one or two styles or heights of collars, are not adapted to easily fit a large number of collars and consequently their use is accompanied by an undesirable projecting or other unsightly improper positioning of the necktie mounted thereon. The peculiar shaping of the collar fold engaging portions of the arms of the Y-member and the collar button engaging portion of the slideable member cooperate to maintain a desirable angle of the necktie holder.

Various modifications in the details of my holder may be made without departing from the spirit of my invention as expressed in the appended claims.

I claim:

1. In a necktie holder, a collar engaging body, and a collar button engaging member slidably mounted on said body so as to maintain the relative angular position between them, said member having a button head receiving opening, the axis of which is substantially at right angles to said member and having a button shank receiving opening, the axis of which is disposed angularly to the axis of said head receiving opening.

2. In a necktie holder, a Y-shaped body member, the stem of which is adapted to serve as a tie holder and the arms of which consists of a single wire having its ends bent in respective planes to engage the fold of a collar to determine the inclination of the stem, a member slidably mounted on the stem of said body member and having a collar button engaging portion disposed at an angle to the remainder of the member and adapted to cooperate with said body arms to determine the inclination of the tie holding stem of the device.

3. In a necktie holder, a collar engaging body member and a two-piece button engaging member, one piece being secured to said body member and extending upwardly with a horizontal flange on the end thereof, the other piece being split and having its parts U-shaped in cross section and yieldingly opposing each other, the legs of each part having opposed saw tooth notches adapted to engage the flange on the other piece.

4. In a necktie holder, a collar engaging body member and a two-piece button engaging member, one piece being secured to said body member and extending upwardly with a horizontal flange on the end thereof, the other piece being split and having its parts U-shaped in cross section and yieldingly opposing each other, the legs of each part having opposed saw tooth notches adapted to engage the flange on the other piece, and projections on said parts which, when pressed together, release the notched parts from said flange.

5. In a necktie holder, a collar engaging body member and a two-piece button en-

gaging member, one piece being secured to said body member and the other piece being of inverted U-shape with its legs slidably mounted on said first piece, when compressed, and tending to separate from each other, said legs and the leg receiving portion of said first piece having interengaging ele-

ments positively holding the two pieces against movement when the legs are not compressed.

In testimony whereof I hereunto affix my signature this 19th day of September, 1922.

JAN CRNOEV.
